By Mark Chapman, Esq.

UNITED STATES PATENT OFFICE.

HERMAN NICHOLS AND HENRY C. ROSE, OF DETROIT, MICHIGAN.

ALARM-BELL.

SPECIFICATION forming part of Letters Patent No. 391,483, dated October 23, 1883.

Application filed May 21, 1883. Serial No. 274,558. (No model.)

To all whom it may concern:

Be it known that we, HERMAN NICHOLS and HENRY C. ROSE, citizens of the United States, residing at Detroit, in the county of Wayne 5 and State of Michigan, have invented certain new and useful Improvements in Alarm-Bells, of which the following is a specification, reference being had therein to the accompanying drawings.

10 This invention relates to new and useful improvements in mechanical bell-alarms; and the invention consists in the peculiar construction and combination of two bells and hammers with a striking mechanism actuated by a vibrating lever, which, when pulled in one direction, causes the hammers to strike alternately and in very rapid succession, while a spring forces the lever to quickly recover its normal position, so as to give the operator a chance to continue the ringing of the alarm indefinitely and almost without a break.

15 The invention further consists in a peculiar locking mechanism, whereby the hammers are arrested to prevent them from accidentally striking when the device is used for bicycles or other vehicles, where it is liable to be heavily jolted.

20 In the drawings which accompany the specification, Figure 1 is an elevation of our device. Fig. 2 is a vertical central section thereof. Fig. 3 is a plan. Fig. 4 is a horizontal section with some of the operating parts removed to show the locking mechanism of the hammers more plainly.

25 A A' are two bells inversely secured to the top and bottom, respectively, of the frame which carries the striking mechanism, and these bells are secured in proximity to each other, so as to leave an aperture, B, between them, through which the actuating-lever C of the striking mechanism projects to the outside. The bells inclose the whole striking mechanism, which consists of a suitable frame formed of the top and bottom plates, a b, secured to 30 each other at a suitable distance apart by means of stays c.

35 D is a shaft journaled in the plates a b, and upon this shaft the inner end of the lever C is made fast.

40 E is a coil-spring sleeved on the shaft D.

One end of this coil-spring is connected to the lever C, and the other end abuts against a stationary part, whereby the tension of the spring is exerted to hold the lever in its normal position shown and to return it to such normal 55 position when the lever is drawn from it.

F is a ratchet-wheel fast on the shaft D.

G is a gear-wheel loose on the shaft D.

H is a spring-click carried by the gear-wheel G and adapted to engage with the ratchet-wheel F, for the purpose of communicating motion in one direction from the ratchet-wheel F to the gear-wheel G.

I is a shaft journaled in the plates a b.

J is a pin-wheel fast upon the shaft I and 65 engaging with the gear-wheel G.

K is a scape-wheel on the shaft I, and T are the pallets engaging therewith to form a so-called "recoil-escapement."

L L' are hammers secured to the shaft M, 70 which carries the pallets, and these hammers are arranged to strike against the bells in opposite directions—one hammer to strike against the upper and the other against the lower bell.

75 N is another shaft journaled in the plates a b, and this shaft is provided with the arms O P, and with a coil-spring, Q, sleeved upon it, the latter being so connected at its free ends that the arm O is held by the tension of said 80 spring in contact with the lever C, whereby in the normal position of said lever, as shown in the drawings, the other arm, P, arrests one of the hammers, thereby preventing both hammers from striking accidentally against the 85 bells.

In practice it will be seen that if the lever C is drawn out of its normal position against the tension of the spring E motion will be imparted to the striking mechanism, and the 90 hammers will alternately strike the upper and lower bell slow or fast, as desired, and if the lever is released as soon as it has reached the limit of its movement it will fly back to its normal position and the operation of sounding the alarm may be repeated. If the operator has obtained a little practice, he may in this manner ring an almost unbroken alarm for any desired length of time, and vary instantaneously the rapidity of the striking to suit his 95 100

fancy or desire. It will further be seen that the arm P, which arrests the hammers when the striking-lever is in its normal position, is drawn out of the way by the spring A as soon as the arm O is not locked in position by the lever C during the sounding of the alarm.

The device may be attached by means of the stem R to any part of a vehicle in proper position for operation either by hand or foot, 10 the lever C being suitably extended or shaped to permit its convenient operation in the desired manner.

We do not deem it necessary to specifically describe all the various applications which can 15 be made of my device, as there are a variety of uses in which bells of this kind are employed, and no invention is needed to adapt our device to the ringing of a door-bell, burglar-alarm, &c., as it is easy to devise suitable 20 means for connecting the lever C with the door-knob or other parts through which the power is mechanically conveyed to actuate the lever C.

What we claim as our invention is—

25 1. In a mechanical bell-alarm, the combination of two bells inversely secured in proximity to each other, the oscillating lever projecting laterally between the two bells, the striking mechanism inclosed between the bells

and actuated by the movement of the oscillating lever in one direction, the spring retracting the oscillating lever to its normal position, and the two striking-hammers, with connections to said lever to cause said hammers to alternately strike the upper and lower bell, 30 substantially as described.

2. In a mechanical bell-alarm, the combination of the two bells, A A', inversely secured in proximity to each other, a striking mechanism inclosed within the bells and provided 40 with the oscillating lever C, projecting laterally between the bells and adapted to convey motion in one direction to the striking mechanism, the hammers L L' within said bells, the spring for retracting the lever C to its normal 45 position, the shaft N, provided with the arms O P, and the spring Q, serving to arrest the hammers in their normal position, substantially as and for the purposes described.

In testimony whereof we affix our signatures, 50 in presence of two witnesses, this 3d day of May, 1888.

HERMAN NICHOLS.
HENRY C. ROSE.
